UNITED STATES PATENT OFFICE

ROSS LANGILL AND STANLEY B. LANGILL, OF MENOMINEE, MICHIGAN, ASSIGNEES TO THE PRESCOTT COMPANY, OF MENOMINEE, MICHIGAN, A CORPORATION OF MICHIGAN

SAWMILL DOG

Application filed April 28, 1927, Serial No. 187,170 Renewed January 9, 1931.

This invention relates in general to sawmill dogs, and more particularly to an improved fluid pressure operated sawmill dog of the type forming the subject matter of the co-pending application of Adolph L. Haase, for sawmill dog, filed June 6, 1925, Serial No. 35,300.

The object of the invention is to provide an improved type of sawmill dog of this character wherein a fluid pressure motor operates through a chain or other similar flexible element for the purpose not only of positively and powerfully urging both log engaging members into proper gripping engagement 15 with the log or board, but also for positively retracting both of the log engaging members. In other words, both log engaging members are positively forced into gripping engagement with the log or board, and both log 20 engaging members are positively forced apart to disengage the log or board.

Another important object of the invention is to provide a sawmill dog of this character which is organized with the knee in such 25 manner that the entire dog may shift back and forth with respect to the face of the knee under the control of a fluid pressure motor whereby the log engaging members may be positioned well out beyond the face of the 30 knee for the purpose of engaging a log or heavy timber, and also may be positioned adjacent the face of the knee for the purpose of engaging a board of relatively thin or light timber.

Another object is to provide a dog of this character wherein the flexible element is so organized with the fluid pressure motor, the frame of the dog and the log engaging members as to impart a straight line movement 40 to the log engaging members in such manner as not to tend to bind the same.

A further object is to provide a dog having the advantages and capacities referred to and which is of simple and durable construction, reliable and effective in operation, 45 easily controllable, and comparatively inexpensive to manufacture.

Other objects and advantages reside in certain novel features of the construction, arrangement and combination of parts which 50

will be hereinafter more fully described and particularly pointed out in the appended claims, reference being had to the accompanying drawings forming a part of this specification and in which:

Figure 1 is a view in side elevation showing a sawmill dog embodying the present invention and organized with a knee plate whereby it is attached to the knee of the sawmill; and

Figure 2 is a view partly in side elevation looking toward the opposite side of the air dog from that shown in Figure 1 and partly in vertical section, the dog being shown mounted on the knee of the sawmill; and

Figure 3 is a view in front elevation of the arrangement shown in Figure 2; and

Figures 4 and 5 are views in horizontal section taken on line 4—4 of Figure 3, but showing the different positions of the dog relative to the face of the knee; and

Figure 6 is a fragmentary view in side elevation similar to Figure 1 but illustrating a different position of the dog relative to the knee face; and

Figure 7 is a fragmentary view in section on line 7—7 of Figure 6.

Referring to the drawings, it will be seen that the dog embodying the present invention includes a frame designated generally at 1, the frame 1 having a horizontal base portion 2, a vertical side portion 3 which may be ribbed for strength and cut out to reduce its weight, and a horizontal top portion 4. Preferably, the frame is a one piece casting, 85 the base portion 2 and top portion 4 of the frame 1 having aligned sockets 5 formed thereon, and in these aligned sockets the ends of a pair of front guide rods 6 and of a single rear guide rod 7 are fitted and secured as by 90 means of pins 8.

On the front guide rods 6 an upper log engaging member designated generally at 9 and a lower log engaging member designated generally at 10 are mounted for vertical sliding movement toward and away from each other. The log engaging members 9 and 10 comprise slides 11 and 12 respectively, the slides 11 and 12 having openings in which the rods 6 are slidably fitted whereby the 100

slides 11 and 12 may be freely adjusted up and down on the rods 6. A downwardly directed log engaging tooth 13 is fixed to and carried by the slide 11 and a similar but upwardly directed tooth 14 is fixed to and carried by an integral extension 12^a of the slide 12.

For the purpose of positively pulling the log engaging members toward each other and into engagement with the log, or the like, and also for positively pulling both of the log engaging members out of the log and away from each other a fluid pressure motor designated generally at F is mounted on the frame and is operatively connected to the log engaging members in a manner which will be herein-after more fully described.

The fluid pressure motor F comprises a movable cylinder 15 having integral apertured guide lugs 16 which slidably receive the guide rod 7 whereby the cylinder 15 is constrained to slide up and down on the guide rod 7. At its ends the cylinder 15 is closed by heads or end members 17 equipped with stuffing boxes 18 through which the upper and lower sections 19 and 20 of a piston rod designated generally at 22 are slidably extended. As shown in Figure 2, the adjacent ends of the sections 19 and 20 of the piston rod 22 are threadedly connected with a piston 23, the piston 23 being a working fit in the cylinder 15. The lower end of the lower section 20 of the piston rod 22 is fastened in any suitable manner to the base portion 2 of the frame, a nut 24 being shown for this purpose in Figure 2. The upper section 19 of the piston rod 22 is similarly fastened to the top portion of the frame, and, in the embodiment of the invention illustrated, a cap 25 is threadedly engaged with the upper section 19 of the piston rod and bears against the top portion of the frame to obtain the fastening action. It will now be understood that with this assembly of the movable cylinder 15 and the stationary piston 23 the cylinder will be moved downwardly when pressure is supplied below the piston 23 and permitted to exhaust from above the piston 23, and on the other hand, the cylinder 15 will be moved upwardly when the pressure is supplied above the piston 23 and permitted to exhaust from below the piston 23.

In order to conveniently supply and exhaust the pressure above and below the piston in the manner required for proper operation, the upper section 19 of the piston rod 22 is made up of concentric tubes 26 and 27, the tube 26 being threaded into the piston 23 and having ports 28 which communicate with the interior of the cylinder 15 above the piston 23. The upper end of this tube 26 is threaded into the cap 25 and communicates with a chamber 29 therein. The tube 27 is threaded into an axial passage 30 provided in the upper end and of the section 20 of the piston rod 22

and communicating at its lower end with a diametrical passage 31 which opens out into the interior of the cylinder 15 below the piston 23. The piston 23 is, of course, formed with an axial opening into which the sections of the piston rod are threaded. The upper end of this inner tube 27 is suitably connected to the cap 25 and communicates with a chamber 32 formed in the cap 25 and entirely separated from and non-communicable with the chamber 29 of the cap. A pipe 33 which leads from any suitable source of supply of fluid pressure connects with the valve casing 34 of a conventional four-way valve 35. The casing 34 has a vent 36 leading to the atmosphere and also has a suitably ported plug 37 which controls communication of the pressure supply pipe 33 and vent 36 with pipe lines 38 and 39 leading to the chambers 29 and 32 respectively.

By turning the valve to one position the fluid pressure supply pipe 33 is placed in communication with the pipe 39 and the pipe 38 is placed in communication with the vent 36, thereby causing fluid pressure to flow into the chamber 32, down through the tube 27 to the passage 30 and thence through the passage 31 into the cylinder 15 below the piston 23. This forces the cylinder 15 downwardly and the air in the cylinder 15 above the piston 23 escapes through the ports 28, the tube 27, the chamber 29, the pipe 38, the valve 35 and the vent 36 to the atmosphere. In another position of the valve, pressure is supplied above the piston 23 to raise the cylinder, and the air below the piston escapes through the tube 27. Then, in a neutral position of the valve, pressure is trapped on both sides of the piston and the cylinder is locked in position.

The downward movement of the cylinder 15 is utilized to pull the log engaging members together to cause them to powerfully and properly grip the log or the like, and in carrying out this purpose the lower end of the cylinder 15 is provided with a pair of lugs 40 which may be cast integral with the cylinder at one side of the center thereof. On these lugs 40, a sprocket wheel 41 is rotatably mounted and meshes with an intermediate portion of a sprocket chain 42. The sprocket chain 42 has one end connected as at 43 with the upper rearward portion of the slide 11 of the log engaging member 9. This chain 42 is then extended downwardly to the sprocket wheel 41 and after passing under and around the sprocket wheel 41 is extended upwardly to a sprocket wheel 44 rotatably mounted on a resiliently supported hanger bracket 45. The bracket 45 has a stud 46 fixed thereto and this stud passes through an opening in the top portion 4 of the frame and is yieldably supported on the frame against downward movement by means of the compression coil spring 47 encircling stud 46 above the frame

and having its lower end engaging the top of the frame and its upper end engaging an adjustable abutment on the stud 46, which abutment may consist of a washer 48 and nuts 49. After passing over and around the sprocket wheel 44 the chain 42 extends downwardly between the guide rods 6 and passes through an opening 11^a provided in the slide 11 (see Figs. 4 and 5) and on down to the slide 12 of the log engaging member 10, the chain 42 being fixed to the slide 12 as indicated at 50 (see Fig. 3). The chain 42 connects with the top of slide 12 near its center and thus exerts an even and direct pull on the slide which moves the same without tending to bind it on its rod 6. The same effect is approximated in respect of the connection of the chain 42 to the slide 11. With this arrangement, when the cylinder 15 moves downwardly the sprocket wheel 41 acts on the chain 42 to cause the chain to pull the log engaging member 9 downwardly and the log engaging member 12 upwardly, thus causing the teeth 13 and 14 of the log engaging members to engage and bite into the log, as illustrated in dotted lines in Figure 2.

The spring 47 and bracket 45 and associated parts provide a tensioning device and shock absorber which takes up slack in the chain 42, and also relieves the other elements of the dog of severe shocks and strains.

The upward movement of the cylinder 15 is utilized to positively pull both log engaging members out of the log and away from each other, and for effecting this operation, a sprocket wheel 51 is rotatably mounted on lugs 52 cast integral with the upper end of the cylinder 15 on the opposite side of the center from the lugs 40 (see Fig. 3). A sprocket chain 53 is fixed as at 54 to the lower rearward portion of the slide 11 of the log engaging member 9 and is then passed up and over the sprocket wheel 51 and down to, around and under a sprocket wheel 55 rotatably mounted on a bracket 56 fastened to the base portion 2 of the frame 1. After passing under and around the sprocket wheel 55 the chain 53 is fixed as at 57 to the upper rearward portion of the slide 12 of the log engaging member 10. When the cylinder 15 moves upwardly, the sprocket wheel 51 acts on the chain 53 to cause it to move the log engaging member 9 upwardly and the log engaging member 10 downwardly, a positive pull being exerted on both log engaging members for disengaging them from the log and moving them apart. However, when the cylinder 15 is moved downwardly and the log engaging members 9 and 10 move toward each other by the action of the chain 42, then the chain 53 is slackened in proportion to permit the chain 42 to bring the log engaging members toward each other.

In the drawings (see Figs. 2, 4 and 5) the centers of the sprocket wheels 41 and 51 are shown slightly offset from each other in a

direction transversely of the sawmill carriage, and while this may be done it has been so shown merely to facilitate illustration and understanding of the arrangement of the chains 42 and 53. In building a dog the axes 70 of the sprocket wheels 41 and 51 will lie in the same vertical plane although these sprocket wheels will be offset slightly in this plane in the direction of the length of the sawmill carriage. 75

To enable the dog to engage either a heavy log or timber or a relatively light board to best advantage it is proposed to mount the dog upon the knee in such a manner that it can be shifted in and out relative to the knee face. In carrying out this purpose a knee plate 60 is provided and is rigidly and securely fastened to the knee 61 by suitable fastening devices. The face of the knee is designated at 62. On this knee plate the frame 1 of the dog is mounted for in and out movement, this mounting being effected by means of headed studs 63 extending through slots 64 in the knee plate 60 and threaded into the frame 1. Antifriction sleeves or collars 63^a 90 are provided on the shanks of the studs 63 and engage the walls of the slots 64. This shiftable mounting of the frame of the dog of the knee plate is also aided by the mechanism employed for effecting and controlling the in and out movement, as will hereinafter more fully appear.

The mechanism for shifting frame 1 in and out comprises a power cylinder 70 suitably fixed to the frame 1 and having a piston 71 fitted therein for sliding movement. Piston 71 has piston rod 72 which projects beyond both ends of the cylinder, the rod 72 extending through stuffing boxes 73 on the end plates of the cylinder 70. The upper and lower portions of the piston rod 72 are formed with racks 74 which are slidably mounted in guides 75 on the frame 1 and which mesh with mutilated pinions 78 having bearing portions 79 journaled or rotatably mounted in bearings 80 provided therefor in the frame 1 (see Figures 2, 4 and 5). Each bearing portion 79 of each pinion 78 has a disk 81 pinned or otherwise suitably fixed thereto. The discs 81 operate in elongated bearing openings or slots 82 provided therefor in the knee plate 60 and these discs 81 have flanges 83 coacting with the frame 1 to hold the discs in the slots 82 and yet leave them free to roll back and forth in these slots. Each disc 81 has an eccentric pin or crank pin 84 threaded therein or otherwise suitably fixed thereto, each pin 84 being pivotally connected to one end of a link 85, the other end of the link 85 being pivotally mounted on a pin or stud 86 threaded into or otherwise suitably fixed to the knee plate 60. Pressure is supplied to either end of the cylinder 70 and exhausted from the opposite end thereof of the control of the conventional four way 130

valve 87 having ports communicating with a source of supply of fluid pressure and with the atmosphere, and also connected with the pipe 88 leading to the opposite ends of the cylinder 70.

Figure 1 shows the dog positioned with the log engaging members retracted or positioned as far inwardly as they may be with respect to the knee face. To project the dog and its log engaging members, fluid under pressure is supplied to the upper end of the cylinder 70 and exhausted from the lower end thereof. This moves the piston 71 downwardly and consequently moves the rack 74 downwardly, thereby rotating the mutilated pinion 78 and consequently the discs 81. As the discs 81 have their crank pins pivoted to the links 85, which are constrained to swing about a fixed axis, the discs 81, when rotated, roll along the slots 82, and when they are rotated by downward movement of the rack 74, they roll from the position shown in Figure 1 to the position shown in Figure 6, thereby moving the dog forwardly with respect to the knee face to project the log engaging members outwardly beyond the knee face as far as they may be projected. Reverse movement of the piston 71 causes reverse operation of these parts and shifts the dog rearwardly on the knee plate to move the log engaging members from the full line position of Figure 6 and the dotted line position of Figures 1 and 2 to the full line positions of Figures 1 and 2.

As clearly shown in Figures 1 and 6, the elongated slots or bearing openings 82 are formed with enlargement 82^a at their ends. This prevents the discs 81 from striking the ends of the slots, the discs merely rolling along the guide portions 82^b of the slots. When the frame 1 and the mechanism carried thereby has been shifted to either of its extreme positions the links 85 are on dead center as will be understood from a comparison of Figures 1 and 6. This makes the shifting means self-locking independently of the fluid pressure, although the fluid pressure in the cylinder 70 also tends to maintain the shifting mechanism and the frame in the extreme position to which they are adjusted.

The discs 81 being constrained to roll back and forth in the slots 82 of the knee plate and being pinned to the pinions 78 which have bearing portions 79 rotatably mounted on the frame 1, aid in the support of the dog on the knee plate, and with the studs 63 and their slots 64 constrain the dog to in and out movement on the knee plate.

From the foregoing it will be understood that the log engaging members not only may be powerfully forced into gripping engagement with the log, but may also be positively withdrawn therefrom. This reverse actuation of the log engaging members may be carried out irrespective of the position of the dog relative to the knee face. In other

words, the log engaging members may be properly controlled and actuated with the dog shifted out relative to the knee face as shown in full lines in Figure 5 and in dotted lines in Figure 2, and also when the dog is shifted 70 in relative to the knee face as shown in full lines in Figures 2 and 4, and in either of these positions the log engaging members may be positively moved in either direction. These advantages are had in an organization which utilizes fluid pressure motors not only for actuating the log engaging members, but also for shifting the dog in and out. The fluid pressure motor which actuates the log engaging members is so organized with the intermediate chain and sprockets, and the intermediate chain is so connected up with the log engaging members that the log engaging members are moved under the action of a direct pull exerted in the line of movement 80 of these members, thereby insuring smooth and easy movement and avoiding tilting or binding.

The invention claimed is:

1. A sawmill dog comprising a pair of log engaging members mounted for sliding movement toward and away from each other, a fluid pressure motor, a flexible element, a guide member mounted on the frame and around which the flexible element is trained and an actuating element shifted by the fluid pressure motor and also engaged with the flexible element, the opposite ends of the flexible element being secured to the log holding members and moving in opposite directions, 100 for causing the flexible element to positively move both log engaging members away from each other when the fluid pressure motor is operated for such purposes.

2. A sawmill dog comprising a frame, a pair of log engaging members slidably mounted on the frame for movement toward and away from each other, a fluid pressure motor, a flexible element having its ends secured to the log engaging members and extended therefrom in substantially the line of movement of said members, said flexible element having a portion freely passing through one of said log engaging members, and rotatable elements mounted on the frame and on the fluid pressure motor and coacting with the flexible element whereby to exert a direct straight line pull on the log engaging members and cause them to be drawn toward each other without binding upon appropriate operation of the fluid pressure motor.

3. A sawmill dog comprising a frame, guides mounted on the frame, a pair of log engaging members including slides slidably interengaged with the guides and also having teeth adapted for engaging the log or the like, a fluid pressure motor mounted on the frame, a pair of flexible elements, each flexible element being connected to both log engaging members, rotatable elements 130

5 mounted on the frame and around which flexible elements are trained and movable actuating elements shifted by the fluid pressure motor and also engaged with the flexible elements whereby the fluid pressure motor serves to positively urge the log engaging members toward each other and also to positively retract both log engaging members.

4. A sawmill dog comprising a frame, 10 guide means mounted on the frame, a pair of log engaging members including slides having openings slidably receiving the guide means and also having teeth for engaging a log or the like, a fluid pressure motor mounted 15 on the frame, flexible elements, and rotatable elements mounted on the frame and on the fluid pressure motor and around which the flexible elements are trained, opposite ends of the flexible elements being connected to 20 the log engaging members and moving in opposite directions upon operation of the fluid pressure motor to positively move the log engaging members toward each other when the fluid pressure motor is operated 25 in one direction and to positively move both log engaging members away from each other when the fluid pressure motor is moved in an opposite direction.

5. A sawmill dog comprising a frame, 30 a pair of log engaging members slidably mounted on the frame for movement toward and away from each other, a fluid pressure motor including a piston having a piston rod fixed to the frame and a movable cylinder in which the piston operates, controllable means for supplying and exhausting fluid pressure to the cylinder above and below the piston whereby the cylinder may be moved in either direction, a flexible element having 35 its ends secured to the log engaging members and extended therefrom in substantially the line of movement of said members, said flexible element having a portion freely passing through one of the log engaging members, a 40 rotatable element mounted on the lower portion of the cylinder and around which an intermediate portion of said flexible element is trained, a resiliently supported rotatable element mounted on the frame and around 45 which the flexible element is also passed, a second flexible element having its ends connected to the log engaging members and extending therefrom in directions opposite to 50 those in which the ends of the first mentioned flexible element extend from the log engaging members, a rotatable element mounted on the frame and around which a portion of the second flexible element passes, and a rotatable element mounted on the upper portion 55 of the cylinder and around which another portion of the second flexible element passes.

6. In a device of the character described, a knee, a sawmill dog having a frame mounted on the knee for in and out movement, fluid pressure motor mounted on the frame, ro-

tatable elements mounted on the frame and actuated from the fluid pressure motor, discs connected to said rotatable elements for movement therewith, said knee having a member provided with elongated bearing openings 70 for the discs, and means coacting with the discs and with said member for causing the frame to move in and out relative to the knee when the rotatable elements are rotated.

7. In a device of the character described, a knee, a sawmill dog having a frame mounted on the knee for in and out movement, a fluid pressure motor mounted on the frame, rotatable elements mounted on the frame and actuated from the fluid pressure motor, discs connected to said rotatable elements for movement therewith, said knee having a member provided with elongated bearing openings 80 for the discs, and links pivotally connected to said discs and to said member for causing the frame to shift relative to the knee when the rotatable elements are rotated.

8. In a device of the character described, a knee, a knee plate secured thereto, a sawmill dog having a frame, means for supporting the frame on the knee plate for in and out shifting movement, a fluid pressure motor including a cylinder fixed to the frame and a piston having a piston rod projecting from the opposite ends of the cylinder and provided with racks, 90 pinions rotatably mounted on the frame and meshed with the racks, discs fixed to the pinions, said knee plate having elongated bearing slots in which the discs are fitted, said discs having flanges to prevent their displacement from the bearing slots, and links eccentrically pivoted to the discs and also pivoted to the knee plate.

9. In a device of the character described, a knee, a knee plate secured thereto, a sawmill 105 dog having a frame, means for supporting the frame on the knee plate for in and out shifting movement, a fluid pressure motor including a cylinder fixed to the frame and a piston having a piston rod projecting from the opposite ends of the cylinder and provided with racks, pinions rotatably mounted on the frame and meshed with the racks, discs fixed to the pinions, said knee plate having elongated bearing slots in which the discs 110 are fitted, and links eccentrically pivoted to the discs and also pivoted to the knee plate.

10. In a device of the character described, a knee, a sawmill dog having a frame mounted on the knee for in and out movement, a fluid 120 pressure motor comprising a cylinder fixed to the frame, a piston fitted in the cylinder and having a piston rod projecting beyond the ends thereof, racks carried by said piston rod, pinions rotatably mounted on the frame and meshed with the racks, and means interposed between the pinions and the knee and operating to cause the dog to move in and out relative to the knee when the pinions are rotated.

11. A sawmill dog comprising a frame, a 130

pair of log engaging members slidably mounted on the frame for movement toward and away from each other, a fluid pressure motor, a flexible element having its ends secured to the log engaging members and extended therefrom in substantially the line of movement of said members, said flexible element having a portion freely passing through one of the log engaging members, a rotatable element actuated by the fluid pressure motor and around which an intermediate portion of said flexible element is trained, a rotatable element mounted on the frame and around which the flexible element is also passed, a second flexible element having its ends connected to the log engaging members and extending therefrom in directions opposite to those in which the ends of the first mentioned flexible element extend from the log engaging members, a rotatable element mounted on the frame and around which a portion of the second flexible element passes, and a rotatable element mounted on the fluid pressure motor and around which another portion of the second flexible element passes.

12. A sawmill dog comprising a pair of log engaging members, a fluid pressure motor and a flexible element operated from the fluid pressure motor and having oppositely moving portions connected to the log engaging members for positively moving both log engaging members away from each other upon appropriate actuation of the fluid pressure motor.

13. In a device of the character described, a sawmill dog mounting, means supporting the sawmill dog mounting for in and out movement, a fluid pressure motor carried by said mounting, rotatable elements journaled on said mounting and geared to and actuated from said fluid pressure motor, and a link for each rotatable element, each link being constrained to oscillate about a fixed axis and being eccentrically connected to its rotatable element.

14. In a device of the character described, a knee, a sawmill dog mounting supported on the knee for in and out movement, a fluid pressure motor carried by said mounting, rotatable elements journaled on the mounting and geared to and actuated from the fluid pressure motor, and links interposed between the rotatable elements and the knee, each link having one end eccentrically pivoted to a rotatable element and having its other end constrained to oscillate about an axis fixed with respect to the knee, said links being positioned on dead center on either extreme position of the dog mounting.

15. A sawmill dog comprising upper and lower opposed log engaging members, guide means constraining said log engaging members to movement toward and away from each other in a vertical plane, a reversely operable motor, means actuated from the motor when

the same is run in one direction to positively urge the log engaging members toward each other, a flexible element, guide and actuating members cooperable with the flexible element and deflecting the same to provide oppositely moving portions, said oppositely moving portions being connected to both log engaging members to positively move both log engaging members away from each other when said flexible element is positively actuated by said actuating member, and a driving connection between said motor and said actuating member for so moving the actuating member as to cause the same to positively actuate the flexible element when said motor is run in an opposite direction.

16. A dog for use on the knee of a sawmill carriage and comprising upper and lower opposed log engaging members, guide means constraining said log engaging members to movement toward and away from each other in a vertical plane, two flexible elements, two sets of guide and actuating members, said sets of guide and actuating members engaging and deflecting said flexible elements to provide oppositely moving portions in each flexible element, one of said moving portions of each element being connected to one of said log engaging members and the other of said moving portions of each flexible element being connected to the other of said log engaging members, the connections of said oppositely moving portions of said flexible elements with said log engaging members being such that when one of said flexible elements is positively actuated by its actuating member it moves the dogs toward each other and when the other is so actuated it moves the dogs away from each other, a reversely operable motor, and driving connection between said motor and said actuating members whereby when said motor is run in one direction the dogs are positively moved toward each other and when the motor is run in an opposite direction both dogs are positively pulled away from each other.

In witness whereof, we hereto affix our signatures.
